Primary Examiner — T Chase Nelson*Assistant Examiner* — Kelly L Gross(74) *Attorney, Agent, or Firm* — McCarter & English, LLP; Jonathan C. Lovely(57) **CLAIM**

The ornamental design for a stent delivery device, as shown and described.

DESCRIPTION

FIG. 1 is a front side elevation view of a stent delivery device embodying my new design;

FIG. 2 is a rear side elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is another perspective view thereof.

The broken lines shown in the figures depict portions of the stent delivery device that form no part of the claimed design.
